UNITED STATES PATENT OFFICE.

EDWARD BORNHOEFT, OF NEW YORK, N. Y., ASSIGNOR TO DAVID H. SCHMIDT, OF NEW YORK, N. Y.

ACTION-BRACKET FOR PIANOS.

SPECIFICATION forming part of Letters Patent No. 728,192, dated May 19, 1903.

Application filed March 18, 1903. Serial No. 148,295. (No model.)

To all whom it may concern:

Be it known that I, EDWARD BORNHOEFT, a citizen of the United States, residing at New York city, (Bronx,) county of New York, and State of New York, have invented certain new and useful Improvements in Action-Brackets for Pianos, of which the following is a specification.

This invention relates to an action-bracket for pianos which is light, of great strength, and permits the ready attachment thereto of the various parts of the action.

In the accompanying drawings, Figure 1 is a side view of my improved action-bracket; Fig. 2, a front view thereof; Fig. 3, a cross-section on line 3 3, Fig. 1; and Fig. 4, a longitudinal section through the supporting screw.

The body of the bracket is made T-shaped in cross-section, being composed of a flat undulating base *a* and of a web *a'*, projecting centrally therefrom. At its top the web *a'* is flattened to form a lug *a*², which lies closely against the upper portion of base *a*. A perforation *a*³ in the lug *a*² and underlying portion of base *a* serves for the reception of a bolt, by means of which the bracket is secured to the wrest-plank. At its bottom the base *a*, as well as the web *a'*, tapers to a blunt point which has a bearing in the concave head of a screw *b*, by means of which the bracket is secured to the key-bottom. To the rear side of base *a* are attached the spring-rail *c*, the action-rail *d*, and the tongue-rail *e*, as usual.

To the web *a'* is secured the arm *f*, which constitutes the support for the hammer-rail. This arm is composed of two halves or sec-

tions and is bifurcated at its lower end to straddle the web *a'*, to which it is secured by transverse rivets *f'*. By this attachment between bracket and arm a very firm and reliable connection is obtained. At its upper or free end the arm is provided with laterally-extending flanges *f*², upon which the hammer-rail is adapted to be supported.

My improved action-bracket is light, of great strength, permits the ready attachment of the various parts of the action thereto, and may be readily mounted within the case.

What I claim is—

1. A T-shaped action-bracket for pianos, combined with rails attached to the base of the bracket, and an arm attached to the web of the bracket, substantially as specified.

2. A T-shaped action-bracket for pianos, combined with a flanged bifurcated arm that straddles the bracket-web, and means for securing the arm to the bracket, substantially as specified.

3. A T-shaped action-bracket for pianos having a web that is flattened at its upper end and tapering at its lower end, substantially as specified.

4. A T-shaped action-bracket for pianos having a flattened perforated upper end, a tapering lower end, combined with a flanged bifurcated arm that straddles the bracket-web, substantially as specified.

Signed by me at New York city, (Manhattan,) New York, this 17th day of March, 1903.

EDWARD BORNHOEFT.
